(57) **CLAIM**

The ornamental design for a surgical mask as shown and described.

DESCRIPTION

FIG. 1 is a front, right, top perspective view of a surgical mask showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the surgical mask in a state of use.

The dashed broken lines in FIGS. 1-7 depict portions of the surgical mask that form no part of the claimed design.

All other broken lines depict environmental subject matter that forms no part of the claimed design.

1 Claim, 8 Drawing Sheets
